UNITED STATES PATENT OFFICE.

LEWIS R. HUMMEL, OF OMAHA, NEBRASKA, ASSIGNOR, BY MESNE ASSIGNMENTS, TO THE ELECTRIC GATE AND SIGNAL COMPANY, A CORPORATION OF NEBRASKA.

TRACK INSTRUMENT FOR RAILWAY SIGNALING.

SPECIFICATION forming part of Letters Patent No. 738,906, dated September 15, 1903.

Application filed August 29, 1902; Serial No. 121,493. (No model.)

To all whom it may concern:

Be it known that I, LEWIS R. HUMMEL, a citizen of the United States, residing at Omaha, in the county of Douglas and State of Nebraska, have invented certain new and useful Improvements in Track Instruments for Railway Signaling; and I do hereby declare the following to be a full, clear, and exact description of the invention, such as will enable others skilled in the art to which it appertains to make and use the same.

My invention relates to track instruments for railway signaling; and it is the object thereof to provide a simple and durable instrument of this character which shall close an electrical circuit when a train passes over the same going in one direction, but which shall not close such circuit when a train passes over the same going in the opposite direction.

An instrument embodying my invention is shown in the accompanying drawings, in which—

Figure 1 is a longitudinal section through the instrument on the planes of the broken line *x x* of Fig. 2. Fig. 2 is a transverse section on the planes indicated by the broken line *y y* of Fig. 1. Fig. 3 is a transverse section on the plane of the line *z z* of Fig. 1; and Fig. 4 is a plan view of the electrical circuit-making contacts, same being a partial section on the plane of the line *w w* of Fig. 1.

In the construction shown a suitable casing 1, having the removable side 2 thereon, is placed adjacent to the rail of a track, so that the wheels of a train passing over the track will extend over and pass above the portion of the casing nearest the rail.

The open top of the casing is covered by the wheel-engaging plates 3 and 4, which have on the under sides thereof the lugs 5, extending inside the casing. The said lugs 5 are connected to the ends of the casing and the block 6 at the central part thereof by pins 7, thus pivoting the plates on the casing at the side thereof farthest from the rail. The edges 8 of the plates 3 and 4 extend over the sides of the casing and are preferably turned down over the same, thus preventing the en-

try into the casing of water and dirt. On 50 the side of the instrument nearest the rail the edges 9 of the plates are turned inward to engage with the lug 10 on the casing. Coil-springs 11, held in position by pins 12 on the casing and plates, normally press upward the inner sides of the plates—*i. e.*, the sides nearest the rail—as far as permitted by the lug 10.

On the under side of the plate 3 and at the end thereof nearest the plate 4 are lugs 13, 60 between which is pivoted the bent lever 24, one arm of which, 14, extends beneath the end of the plate 4 and the other arm, 15, extends downwardly, as shown in Figs. 1 and 2. A small spring 16 presses against the arm 15 65 of the lever 24 and normally holds the arm 14 up against the plates 3 and 4.

On the side of the casing 1 and on the block 6 are blocks of insulating material 17, to which is secured the metallic contact-strip 18, the 70 same extending diagonally across from one insulating-block to the other, as shown in Figs. 1, 2, and 4. On the bottom of the casing is an insulating-block 19, to which is secured the spring-contact 20, which extends 75 upwardly adjacent to the contact-strip 18 and between the same and the block 6.

Wires 21 and 22 are attached to the contacts 18 and 20 and extend outside the casing through the pipe 23 to any signaling apparatus with which the track instrument may be used.

The operation of the device is as follows: A train passing over the track in the direction of the arrow A, Fig. 1, the wheels thereof engage with and tilt the plate 3 by depressing the inner side thereof against the tension of the spring 11. The tilting of the said plate throws the depending arm 15 of the lever 24 between the contact-pieces 18 and 20, 85 thus closing the electrical circuit through the wires 21 and 22. The positions of the plate and lever when tilted are shown in dotted lines in Fig. 2. The wheels of a train moving in the direction indicated by the arrow B, Fig. 1, tilt the plate 4 before reaching and tilting the plate 3. When the plate 4 is tilted and the inner side thereof depressed, the same pushes down the

horizontal arm 14 of the lever 24, thus pushing the depending arm 15 against the tension of the spring 16 to the position shown in dotted lines in Fig. 1. The wheels then striking, tilting, and depressing the plate 3, the arm 15 instead of being pushed between the contacts 18 and 20 passes over and outside of the contact-strip 18, so that electrical connection is not made between 18 and 20, and the circuit remains open.

It is obvious that the mechanism described while presenting an effective means of accomplishing the objects hereinbefore set forth is exceedingly simple and having few moving parts is durable and not likely to be broken or disarranged. It will also be noted that the electrical connections being made by rubbing-surfaces the contacts will be kept bright and clean and that the manner of inclosing the operating parts prevents access of injurious material thereto.

Now, having described my invention, what I claim, and desire to secure by Letters Patent of the United States, is—

- 25 1. In a railway signaling track instrument a casing, wheel-engaging plates pivoted thereon, a lever pivoted on one of said plates, an arm on said lever adapted to engage the terminals of an electrical circuit when the said plate is tilted, and a second arm on said lever engaging with the other plate, the arrangement being such that when the latter plate is tilted before the former the terminals of the electrical circuit will not be engaged.
- 35 2. A track instrument for railway signaling comprising a casing, two tilttable wheel-engaging plates pivoted thereon and forming a cover therefor, a lever pivoted on one of said plates, and contact-pieces forming the terminals of an electrical circuit, one arm of the said lever normally engaging with the plate on which

the lever is not pivoted, and the other arm of the lever being adapted to engage with the said contact-pieces when the plate carrying the lever is tilted before the other plate but 45 not to engage said contact-pieces when the plate carrying the lever is tilted after the other plate.

3. A track instrument for railway signaling comprising a casing, two wheel-engaging 50 plates pivoted on said casing, overhanging edges on said plates extending over said casing, one of said edges engaging a lug on said casing, springs normally holding said edge against said lug, a lever pivoted on one of said plates and engaging with the other of said plates, a spring normally maintaining said engagement, and a portion of said lever adapted to engage the terminals of an electrical circuit when the plate carrying the lever is 55 tilted.

4. A track instrument for railway signaling comprising a casing, two wheel-engaging plates pivoted on the casing, a lug on the casing, edges on the plates engaging said lug, 60 springs normally maintaining said engagement, contact-pieces forming the terminals of an electrical circuit, and a lever pivoted on one of the plates, engaging with the other of said plates and extending to a position adjacent to the said contact-pieces, the arrangement being such that a train passing over the instrument in one direction will throw the lever into engagement with the contact-pieces while a train passing in the opposite direction 65 will not cause such engagement.

In testimony whereof I hereunto affix my signature in presence of two witnesses.

LEWIS R. HUMMEL.
